BED RAIL CONNECTER

Filed Feb. 15, 1928

UNITED STATES PATENT OFFICE

ADOLF WESTON, OF LOS ANGELES, CALIFORNIA

BED-RAIL CONNECTER

Application filed February 15, 1928. Serial No. 254,476.

My invention relates to connectors for bed rails of the character embodied in my co-pending application, Serial No. 214,908, filed August 23, 1927, and it is the purpose of my present invention to so modify the construction of connectors of this character as to render the side bed rails reversible to accommodate what is termed in the art as flat bed springs or coiled or box bed springs, and 10 in such manner that each is supported at the same level on the bed frame.

I will describe only one form of bed rail connector embodying my invention and will then point out the novel features in claims.

15 In the accompanying drawings:

Fig. 1 is a view showing in perspective one form of bed rail connector embodying my invention in applied position to the rails and one post of a bed frame and with the elements 20 thereof connected to each other;

Fig. 2 is a view similar to Fig. 1 showing the same side rail of the bed frame as that shown in Fig. 1 reversed and applied to the opposite or adjacent bed post;

25 Fig. 3 is a detail perspective view of that element of the connector adapted to be secured to the bed post; and

Fig. 4 is a similar view showing that element of the connector which is applied to the 30 side rail of the bed frame.

Referring specifically to the drawings, my invention in its present embodiment comprises a connector made up of two main elements designated generally at E and E', the 35 element E being adapted for connection to a bed post B and to an end rail R, while the element E' is adapted for permanent connection to a side rail R', it being understood that the rails R and R' are parts of a conventional bed frame, and in the form of angle bars.

The element E comprises a plate 15 of metal or other suitable material secured to one side of the bed post B by means of three screws 16, the lowermost one of which is extended through the adjacent end of the end rail R. Along its outer vertical edge the plate 15 is provided at vertically spaced points with upwardly extending hook members 17 having rounded outer edges as illustrated. At one side but between the hook

members 17 is secured within the plate 15 a headed projection 18 designed for the purpose of detachably securing the element E' on the element E.

The element E' is constructed from a relatively short length of angle-iron so as to provide portions 19 and 20 disposed at right angles to each other, the portion 20 extending into a slot 21 in the horizontal portion 22 of the side rail R' so that the vertical portion 23 of the rail is disposed at the outer side of the portion 20. The rail is permanently secured to the portion 20 so as to be disposed in right-angular relation to the element E'. The portion 19 of the element E' is reduced in width 55 adjacent its opposite ends to provide a relatively wide intermediate portion 19^a, the opposite ends of which provide transverse shoulders 19^b and 19^c. Intermediate its ends the portion 19^a is provided with an opening 19^d, the upper and lower walls of which are shaped to provide sockets 19^e and 19^f in either of which the shank of the projection 18 is adapted to seat when the elements of the connector are assembled. The adjacent end of 60 the horizontal portion 22 of the side rail R' spans the opening 19^d medially of its ends, and this end of the rail is recessed as indicated at 22^a in order to provide the necessary clearance for the headed projection 18 in applying 65 the element E' to the element E. The portion 19 adjacent its point of connection with the portion 20 is formed with vertically extending and vertically spaced slots 24 through which the hook members 17 of the element E are 70 adapted to be extended.

In the applied position of the element E' on the element E, as illustrated in Fig. 1, the hook members 17 are first extended into the slots 24 when the element E' is forced downwardly causing the hook members to firmly engage and support the element E' thereon. The limit of downward movement of the element E' is defined by the hook members 17, the headed projection 18, and the transverse shoulder 19^c. Consequently, the element E' has four points of support on the element E and as a result distributes the load imposed on the side rail evenly along the length of the element E. As in the bed rail embodied in 75 80 85 90 95 100

my copending application, above referred to, the headed projection 18 functions to secure the element E' against horizontal movement on the element E so that the two elements are 5 fixedly secured in right-angular position. It is important to note that the shape of the portion 19 of the element E' is such as to escape or clear the heads of the two upper screws, thus eliminating the necessity of countersinking 10 into the screw-heads.

The bed rail connector, as illustrated in Fig. 1, may be considered as applied to the left-hand bedpost to connect the left-hand side rail thereto, and in this position of the side 15 rail the portion 22 is disposed uppermost and constitutes the surface upon which a bed spring of the flat type is supported. If it is desired to support a coiled bed spring or a 20 box spring, the side rails R' should be inverted so that each rail assumes the position shown in Fig. 2. In this inverted position, the portions 23 extend upwardly from the 25 portions 22 instead of downwardly and they thus function to engage the sides of the springs to prevent edgewise displacement of the springs. The construction of my connector is such as to permit inversion of the side rails, and by a comparison of Figs. 1 and 30 2 it will be manifest that the element E' in either position can be applied to either element E of either bedpost to cause the hook members and headed projection to engage and 35 secure the element E' in fixed relation to the bedpost, and that in either position the element E' is supported at four points along its length, the shoulder 19^b engaging the rail R in the inverted position shown in Fig. 2, and a headed projection 18 seating within the socket 19^c.

In the inverted position of the element E', the horizontal portion 22 of the side rail R assumes the same horizontal position as it did when in the position shown in Fig. 1, and, consequently, the side rail will continue to 45 support a bed spring in the same horizontal position as it did when in the position shown in Fig. 1. It will, therefore, be manifest that my connector is such as to permit what is known in the art as reversing of the bed rails 50 and yet functioning to support the bed springs in the same horizontal plane.

Although I have herein shown and described only one form of bed rail connector embodying my invention, it is to be understood that various changes and modifications may be made herein without departing from the spirit of the invention and the spirit and scope of the appended claims.

I claim:

60 1. A bed rail connector comprising an element having hook members thereon and a headed projection, said element adapted to be secured to the end rail of a bed frame, and a second element adapted to be secured to the 65 side rail of a bed frame and having angularly

disposed portions, one of which is slotted to receive the hook members, provided with an opening, the walls of which are shaped to form reversely disposed sockets in either of which a headed projection is adapted to seat, and so shaped as to form spaced transverse shoulders either of which is adapted to abut the end rail.

2. In combination, a bed frame having an end rail and a side rail of angular form in 75 cross-section; an element adapted to be secured to a bedpost and to the end rail, vertically spaced hook members on said element, a headed projection on said element, a second element having angularly disposed portions, 80 said side rail having its horizontal portion slotted to receive one portion of the second element and secured thereto, the other portion of the second element having slots to receive the hook members, provided with an opening, the wall of which is shaped to form oppositely disposed sockets in either of which the headed projection is adapted to seat, the horizontal portion of the adjacent end of the side rail being recessed to provide the necessary clearance for the headed projection in moving it into either of said sockets, the said second element being so shaped as to provide spaced horizontal shoulders either of which is 85 adapted to seat on the end rail.

Signed at Los Angeles, in the county of Los Angeles and State of California, this 6th day of February, A. D. 1928.

ADOLF WESTON.
